CLAIM

The ornamental design for a wireless internet vending machine, as shown and described.

DESCRIPTION

FIG. 1 is a front perspective view of the wireless internet vending machine of the present invention showing my new design with the broken lines depicting solely environmental structure and forming no part of the claimed design;

FIG. 2 is a top plan view thereof;

FIG. 3 is a front elevational view thereof;

FIG. 4 is a side elevational view thereof;

FIG. 5 is a bottom plan view thereof; and,

FIG. 6 is a rear elevational view thereof.
